(57) **CLAIM**

The ornamental design for lubricant feeder, as shown and described.

DESCRIPTION

1.1 is a front elevation view of a lubricant feeder showing our new design;

1.2 is a rear elevation view thereof;

1.3 is a left side elevation view thereof;

1.4 is a right side elevation view thereof;

1.5 is a top plan view thereof;

1.6 is a bottom plan view thereof;

1.7 is a top left front perspective view thereof;

1.8 is a top left front perspective view thereof, shown with some environmental structure removed;

1.9 is a top plan view thereof.

The broken lines shown in the reproductions depict environmental structure or portions of the lubricant feeder and form no part of the claimed design.
